UNITED STATES PATENT OFFICE.

HERBERT WILEY HETHERINGTON, OF PROVIDENCE, RHODE ISLAND, ASSIGNOR TO THE J. C. HALL COMPANY, OF PROVIDENCE, RHODE ISLAND, A CORPORATION OF RHODE ISLAND.

DESIGN FOR SAFETY PAPER.

Application filed September 2, 1925. Serial No. 14,700. Term of patent 14 years.

To all whom it may concern:

Be it known that HERBERT WILEY HETHERINGTON, a subject of the King of Great Britain, residing at Providence, of the county of Providence and State of Rhode Island, has invented a new, original, and ornamental Design for Safety Paper, of which the following is a specification, reference being had to the accompanying drawing, forming a part thereof.

The figure is a plan view of a portion of a sheet of paper embodying my new design.

I claim:

The ornamental design for safety paper substantially as shown.

In testimony whereof I affix my signature.

HERBERT WILEY HETHERINGTON.
